UNITED STATES PATENT OFFICE

ALBERT NAU-TOURON, OF GRASSE, FRANCE

AUTOMATIC THREAD-TENSION REGULATOR FOR CONTINUOUSLY-ACTING SPINNING MACHINES

Application filed October 14, 1926, Serial No. 141,681, and in France October 17, 1925.

In the continuous acting spinning machines at present employed, it is well known that the tension of the thread depends on certain differences in the linear, circumferential and angular velocities of the moving parts concerned, and on certain forces external to the system on certain couples and on certain moments.

It is also known that, systematically, the momentary values of equilibrium are variable as they are derived from equilibrium data which are variable themselves, and that unless the desired equilibrium be reestablished, the tension of the thread will be essentially variable from the commencement of the winding of the thread formed, on the bobbin up to the end, that is to say throughout the course of the formation of the bobbin. It is therefore necessary to keep this tension always constant and equal to the value selected, namely to apply to the bobbin a supplementary mechanical braking action known as "drag".

This supplementary resistance must be calculated as a function of the momentary diameter of the winding so as to obtain a constant tension.

In present practice and especially in the spinning of flax, the worker is compelled to exercise an incessant watch and is caused much fatiguing labour, because at every instant he has to move the "drag" weights in such a way as to augment the arc of contact of the bobbin with the brake cord in proportion to the winding.

The present invention relates to a compensating apparatus which acts automatically and the object of which is to give to the thread a tension which can be regulated during the formation of the bobbin and to automatically maintain this constant tension during the entire operation without its being necessary for worker to intervene for all the spindles or for each spindle taken individually.

The principle of the invention consists in replacing the rising and falling rack, or "drag" bar ordinarily fixed in spinning machines, by a "drag" bar to which an intermittent and longitudinal movement is imparted in proportion to the phases of formation of

the various layers of thread on the bobbin, augmenting the braking action in such a way that the diameter of this bobbin increases, that is to say as a function of the thickness proper of the finished thread.

In the accompanying drawings is diagrammatically shown, by way of example, a constructional form of the invention applied to a spinning machine of the continuously acting type with side pieces.

Figure 1 is a front elevation of a portion of the machine with the rising and falling rack broken away, and its connections with the apparatus, characteristic of the invention.

Figure 2 is a corresponding plan view partly in section.

Figure 3 is a detail view of the driving apparatus in elevation.

Figure 4 is a plan view of the same.

Figure 5 is a sectional view of the rising and falling bar and of the mounting of the "drag" weights along the line 5 5 of Figure 1.

Figure 6 is a sectional view, on the line 6 6 of Figure 2, these two figures, 5 and 6, being drawn to a larger scale in comparison with the preceding figures; finally,

Figures 7 and 8 represent, in vertical section and in plan, a special device for mounting the bobbins.

The rising and falling rack or "drag" bar in machines constructed according to this invention, is replaced by continuous and movable bar 1 which is adapted to slide along the rising and falling plate 0 on a roller track or raceway 2 so as to reduce the resistance due to friction. On this bar 1 is also adapted to slide another bar 3 with or without the interposition of rollers. This second bar 3 is constantly forced towards the apparatus which operates it, that is to say towards the left, in Figure 1, by means of a compression spring 4 which acts by compression. Conduits shown in Figures 1 and 5, in the form of sheaves 5, are mounted on swivelling supports 6 on the members 7 (see Figures 1 and 5) which by means of slots 8 set screws 9 and guide pins 10 with heads 11,

can be subjected to a certain amount of individual adjustment longitudinally.

The members 5 are equal in number to the number of spindles, and are, when the machine is working normally, a corresponding 5 distance apart.

To the opposite edge of the rising and falling plate 0 is fixed another bar 12 which, within certain limits, can be regulated as to position longitudinally with respect to the 10 rising and falling plate itself.

This bar carries blocks 13 pierced with an eye and adapted to rock freely about it around axes 14. The brake cord 15 is fixed at its free end to the member 13, passing 15 through the eye, and secured by means of a knot 16 in the usual way.

The eyes 13 may be either completely closed or they may be split at their upper ends so as to facilitate the putting on of the cord.

20 The cord 15 runs in a horizontal plane, bearing against a certain part of the circumference of the groove in the base of the bobbin, then over the sheave 5 and terminates in a drag weight 17.

25 The end of the bar 1a where the apparatus which operates it is located, that is to say towards the left in Figure 1, is pivoted at a point 18 to a shoe 19 adapted to slide on the 30 edge of the rising and falling plate and has a boss 20 which is adjustably connected by a suitably shaped member 21 to a stirrup of yoke 22 oscillating freely about an axis 23 carried by the flat piece 24.

35 The member 24 is mounted on round rods 25, 25a which are adapted to slide freely in the sockets 26, 26a of a support 27 and firmly secured by any suitable means to the rising and falling plate.

40 The rods 25, 25a are fixed at their opposite ends to a member 28 that is provided with an opening or longitudinal groove 29. The opening 29 receives a crank pin 30, which can be secured, by means of nuts 31, to a 45 plate or drum 32 on which the crank pin 30 is adjustable radially by means of a screw 33 provided with a nut and a lock nut and with the groove 34.

50 The plate or drum 32 has another radial groove 35 in it preferably in line with the groove 34 and by means of which it can have a rotary motion imparted to it according to a certain law of angular variation by means of the trunnion 37 attached to the pinion 36 55 and adjustable radially thereon by means of the regulating and locking stud 38.

In order to permit of the free rotation of the drum 32 relatively to the ring 39, this 60 drum is mounted on ball bearings 40 or bearings of a similar kind.

65 The ring 39, the body of which is connected to the rising and falling plate 0, carries an internally toothed ring 39a which gears into the teeth of the satellite pinion 36, the ratio

of the transmission of these two gears being preferably 1 to 2.

By simple regulation of the stud 38 and of the crank pin 30 it is possible to obtain a whole gamut of laws and amplitudes of movements of the bar 1 and consequently of the sheaves 5 of the brake cords.

The satellite pinion 36 rotates loosely on a trunnion or stud axle 41, attached to a plate 42, keyed on a shaft 43 carrying on its rear end a gear wheel 44 suitably pinned.

75 The wheel 44 (see Figures 3 and 4) gears into a pinion 45 keyed on the shaft 47 of a worm wheel 46. The shaft 47 rotates in a bearing (not shown) in the support 48 likewise connected to the rising and falling plate 0. The support 48 has an upper stirrup or yoke which receives the shafts of a worm 49 gearing into the worm wheel 46.

80 This worm 49 is integral with a ratchet wheel 50, in gear with pawls 51, 51a constantly drawn into engagement with the ratchet wheel by means of springs 52, 52a.

85 By means of pins 53, 53a the pawls 51, 51a are themselves connected to a disc or plate 55 which carries extensions 56 and 57 of suitable shape. The ends of these extensions are provided with bosses 58 and 59.

90 Along the axes of each of these bosses or in line with the same are arranged stops constituted by screw threaded rods 60 and 61 which, by means of helical or similar springs and nuts and lock nuts, can be adjusted in position longitudinally in the respective sockets 62 and 63 pierced with graduated 95 openings or slots 64 and index drawn on the rod permitting the position of the stops to be set accurately to agree with the graduated scale for the purpose of regulation.

100 The stop formed by the whole 61-62 is connected to the rising and falling bar by a suitable support 65, shown as being broken away in Figure 3, while the whole of the stop 60, 63 is connected to the frame 66 of the spinning machine, that is to say fixed with respect to the movements of the parts in motion.

105 A helical spring 67 working constantly under traction and adjustable by means of a nut and lock nut, connects on the one hand the support 65 of the stop 61 and on the other hand the arm 56 of the disc 55 to the point 68. In consequence hereof the action of the spring 67 constantly draws the boss 58 and the stop 61 towards each other.

110 The combination of the mechanical parts described acts as follows:

115 If it be supposed that empty bobbins 69 are placed in the spinning machine, the rising and falling bar being at the top of its stroke, the operator will commence by regulating the rear bar 12 in such a way that the cords 15 are brought into contact with the groove at the base of the bobbin along a development corresponding to a desired angle β .

The bar 12 will be brought into this position by means of the device shown in plan in Figure 2 and in vertical section in Figure 6 and which consists of a shaft 70 on which is keyed a toothed sector 71 gearing into a rack 72 fixed to the lower face of the bar 12.

The movement of this bar will have brought the eyes 13 to the point corresponding to the value sought by the angle β . The 10 sector 71 is keyed or locked in position by acting on the nut 73 with the handle which through the medium of a washer forces the operating crank 74 from its base (see Figure 6).

15 When the spinning machine is started or restarted, the operator begins by moving the lever 75 in the direction of the arrow 76, to push, in the direction opposite to that in which it is driven the whole of the bar 1 so 20 as to facilitate the starting of the bobbins.

Stops 77 and 78 respectively are fixed to the end of the bar 1 and to the end of the rising and falling plate.

The regulation of these stops will always 25 be effected in such a way that the angle α corresponding to the development of the remaining part of the brake cord on the groove of the bobbin shall be practically nothing at the commencement of the rise. The stop 78 30 is hinged so as to permit, should it be necessary, of the disconnecting movement being augmented.

The position of the stops 60 and 61 is then regulated according to the graduated scale 35 engraved on the sockets 63 and 62 constructed according to certain calculations which depend essentially on the numbers of threads to be executed on the machine.

The machine is then started, that is to say 40 that if a start was made from the upper position of the rising and falling bar, this latter will begin to descend, then by means of the well known mechanical devices employed will again begin to ascend. When it arrives again 45 at the top of its stroke the boss 59 which, as above stated is connected through the medium of various members to the rising and falling bar 0 strikes against the end of the stop 60, tending to cause the whole of the arms 57 and 56 to turn in the direction of the direction of the arrow 79. Under these conditions, the 50 pawls 51 and 51a will engage with the teeth of the ratchet wheel 50 and will cause it to rotate a certain number of teeth, during a 55 certain portion of the upward stroke of the rising and falling bar in consequence of the adjustment of the stop 60 the stop 61 serving simply to limit the stroke of the arm 56 to an 60 angular value equal at least to that of the stroke of the arm 57.

As soon as the rising and falling bar has commenced to descend again, the action of the spring 67 puts the pawls 51 and 51a into engagement again with the teeth of the 65 ratchet wheel, and the apparatus which con-

trols the movements of the conduits of the drags is ready for the next operation.

It will be noted that the rotation of the ratchet 50 causes rotation of the worm 49 and therefore through the medium of the gears 46, 45 and 44 the plate 42 and the satellite pinion 36 are rotated, thus rotating the drum 32 to cause linear movement of translation of the bar 1.

The direction of movement being determined in advance it follows that at the moment when the rising and falling bar which has started from the top of its stroke or travel to the top of its stroke or travel, the bar 1 and the bar 3 supported by it and also the thread guide 5 are moved towards the left in Figure 1 by a certain amount so that the angle α of contact of the brake cords with the grooves in the bobbins has been augmented automatically and by the quantity determined and so augmented also for all the bobbins at once.

In proportion to the working of the machine, and every time the rising and falling bar returns to the top of its stroke or travel, the same change will be produced, in such a way that each complete reciprocation of the rising and falling bar is succeeded by a fresh increasing in the angle of contact of the brake, which augmentation is essentially intermittent and corresponds exactly to the formation of a fresh layer of thread.

When the bobbin is finished and when it is required to set the machine going again for a fresh bobbin, this can be done by turning the crank handle 79 to cause the worm 49 on which it is keyed to rotate in the reverse direction to that of the preceding movement so as to bring all the parts back to the starting point, then the machine will be started again, 100 as described above, the same phases being reproduced up to the end of the winding operation.

Figures 7 and 8 show in vertical section and in plan respectively a particular arrangement of bobbin applicable to the invention. In this case the bobbin 69 has a smooth base 69a, in which is formed a seating 69b. By means of this arrangement the action of the 110 brake cords can be applied by means of a metal washer 80 having a groove 81 and a slip pin 82 which extends into the seat 69b of the bobbin 69 to cause the bobbin to rotate the washer 80.

The advantage of this latter device is that the uniformity and the regularity of the grooves is thus assured for all the bobbins.

It must be quite understood that all changes of constructional materials of the parts described or all changes in the position of these parts relatively to each other, or all changes in details of execution must be considered as being within the scope of the present invention.

Claims:

1. An automatic thread tension regulator for spinning machines having bobbins, said regulator comprising a bar movable longitudinally and disposed adjacent one side of said machine, a bar that is spring pressed in a longitudinal direction and is slideable on said first named bar, brake bands contacting with said bobbins, and brake band carrying means mounted on said second-named bar causing said brake bands to press against said bobbins.
2. An automatic thread tension regulator for spinning machines having bobbins, said regulator comprising a bar movable longitudinally and disposed adjacent one side of said machine, a spring pressed bar slideable on said first named bar, brake bands, and brake band guides carried by said last named bar and adjustable longitudinally along said bar, said brake bands contacting with the bobbins of said spinning machine.
3. An automatic thread tension regulator for spinning machines having bobbins, said regulator comprising a bar movable longitudinally and disposed adjacent one side of said machine, a spring pressed bar slideable on said first named bar, brake band guides carried by said last named bar and adjustable longitudinally along said bar, a plurality of spindles adjacent said bars, brake bands contacting with said bobbins, and an adjustable bar to which said brake bands are attached located on the other side of said spindles from said first named bars.
4. In an automatic thread tension regulator for spinning machines, a bar movable longitudinally and disposed adjacent one side of said machine, and a reciprocating frame attached to said bar, said frame being provided with a groove, and a crank pin in said groove for operating the same in a direction parallel to said bar to move it longitudinally.
5. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame.
6. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame, said means comprising a disc carrying a radially adjustable crank pin.
7. In an automatic thread tension regulator for spinning machines having spindles, bobbins carried by said spindles, a brake band carrier, brake bands for said bobbins,

a reciprocating frame attached to said carrier, a reciprocating bobbin rail, and means operated by the up and down motion of said rail for reciprocating said frame, said means comprising a disc carrying a radially adjustable crank pin, a radial groove in said pinion and a satellite gear carrying a member operating in said groove.

8. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame, said means comprising a disc carrying a radially adjustable crank pin, a radial groove in said pinion, a satellite gear carrying a member operating in said groove, an internally geared ring carried by said plate and meshing with said satellite gear.

9. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame, and adjustable stops to regulate the amount of movement of said frame.

10. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame, and adjustable stops to regulate the amount of movement of said frame, said means comprising a pawl and ratchet mechanism.

11. In an automatic thread tension regulator for spinning machines having spindles, bobbins carried by said spindles, a brake band carrier, brake bands for said bobbins, a reciprocating frame attached to said carrier, a reciprocating bobbin rail, and means operated by the up and down motion of said rail for reciprocating said frame, and adjustable stops to regulate the amount of movement of said frame, said means comprising a pawl and ratchet mechanism, an internally toothed ring, and a satellite pinion that has half as many teeth as said ring.

12. In an automatic thread tension regulator for spinning machines having spindles and bobbins on said spindles a bar movable longitudinally and disposed adjacent one side of said machine, a spring pressed bar slideable on said first named bar, said last named bar carrying brake band guides adjustable longitudinally along said bar, brake bands, and means whereby said brake bands
